SMOKER'S PIPE

George McCullough, Akron, Ohio

Application August 5, 1941, Serial No. 405,531

1 Claim. (Cl. 131—195)

This invention appertains to new and useful improvements in smoker's pipes, the principal object of the same being to provide a pipe constructed in such a manner as to cool the smoke drawn from the pipe bowl before it reaches the smoker's mouth.

Another important object of the invention is to provide a pipe which has a condenser in use therewith and adapted to cause condensation of any water vapors that might normally be drawn into the smoker's mouth with smoke from the pipe bowl and to also cause precipitation of any foreign matter in the smoke path through the pipe stem.

Other objects and advantages of the invention will become apparent to the reader of the following specification.

In the drawing:

Figure 1 represents a side elevational view of the pipe with the bowl end portion in section.

Figure 2 is a sectional view taken substantially on the line 2—2 of Figure 1.

Figure 3 is a side elevational view, partly in section, showing the deflector of the condenser.

Referring to the drawing wherein like numerals designate like parts, it can be seen that numeral 5 denotes a bowl structure having a tobacco receiving cavity 6 and extending from this bowl structure 5 is a stem 7 having a duct 8 extending therethrough, this stem having a mouthpiece 9 connected thereto.

Where the stem 7 merges with the bowl structure 5 an enlargement 10 is located and this has a vertical bore therein defining a compartment 11 which forms part of the condenser generally referred to by numeral 12 and which is incorporated in the smoke path of the pipe.

The bore defining the chamber 11 extends upwardly from the bottom of the formation 10 and in the lower portion of this bore is disposed a plug 13 having a small opening therethrough for snugly receiving the lower end of a tube 14. The upper end of this tube 14 has a threaded head portion 15 which is threadedly disposed in an internally threaded and flanged bushing 16 set in the upper portion of the body formation 10. It is preferable that the upper portion of the tube 14 be kerfed or otherwise formed to accommodate a tool when the tube 14 is to be unscrewed.

As shown in Figure 3, numeral 17 denotes a

sleeve snugly surrounding the tube 14, as shown in Figure 1, and this sleeve 17 has a pair of side wings 18 extending in opposite direction and terminating a substantial distance below the upper end of the sleeve 17. The lower ends of these wings 18 depend a slight distance below the lower end of the sleeve 17 so as to seat in shallow recesses in the plug 13.

A short duct 19 extends from the pipe bowl chamber 6 to the chamber 11 and as is shown in Figure 1, the stem duct 8 communicates with the chamber 11.

As the wings 18 extend to snugly engage and preferably fit in grooves in the inner side portions of the formation 10, smoke from the bowl chamber 6, passing through the duct 19 must pass upwardly in the chamber 11 at one side of the sleeve 17 until it reaches the upper ends of the wings 18 at which point the smoke passes around the upper portion of the sleeve 17 and downwardly on the other side of the sleeve to the duct 8. Thus the smoke is caused to follow a vertical offset path and this will have a tendency to precipitate any water and foreign matters of a heavy nature, following the smoke path.

Obviously, to remove the condenser structure, the tube 14 is first unscrewed and removed, after which the sleeve 17 can be pushed downwardly to remove the plug 13.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

A smoker's pipe comprising a bowl, a stem, a smoke duct extending from the bowl through the stem and a deflector on the stem for causing a vertically disposed upwardly and downwardly deflection of the smoke path, said deflector consisting of a chamber on the side of the bowl, an air tube extending through the chamber and a sleeve on the tube having lateral partitions and terminating adjacent the upper end of the sleeve to afford a by-pass for smoke at the upper end of the chamber.
